US0D1041844S

(12) **United States Design Patent** (10) **Patent No.:** **US D1,041,844 S**
(45) **Date of Patent:** **** Sep. 17, 2024**

(54) **SOLE**

(71) Applicant: **adidas AG**, Herzogenaurach (DE)

(72) Inventors: **Maurice Takyi Essilfie-Taylor**, Nuremberg (DE); **Arnau Sanjuan Roman**, Nuremberg (DE); **Andrew Graham Turner**, Nuremberg (DE)

(73) Assignee: **adidas AG**, Herzogenaurach (DE)

(**) Term: **15 Years**

(21) Appl. No.: **29/773,611**

(22) Filed: **Mar. 10, 2021**

Related U.S. Application Data

(63) Continuation of application No. 29/653,097, filed on Jun. 12, 2018, now Pat. No. Des. 913,663.

CLAIM

The ornamental design for a sole, as shown and described.

DESCRIPTION

The FIGURE is a bottom view of a sole showing the claimed design.

The FIGURE is illustrated to show contrasting appearance. The gray-shaded portions of the sole have one appearance and the non-shaded claimed portions have a different appearance.

1 Claim, 1 Drawing Sheet
